UNITED STATES PATENT OFFICE.

KARL FRITJOF NYSTROM, OF ST. LAMBERT, QUEBEC, CANADA.

CAR CONSTRUCTION.

1,254,346.

Specification of Letters Patent.

Patented Jan. 22, 1918.

Application filed February 19, 1917. Serial No. 149,597.

To all whom it may concern:

Be it known that I, KARL FRITJOF NYSTROM, a subject of the King of Sweden, and resident of 80 Edison avenue, in the town 5 of St. Lambert, Province of Quebec, in the Dominion of Canada, have invented certain new and useful Improvements in Car Construction, of which the following is the specification.

10 The invention relates to improvements in car construction as described in the present specification and illustrated in the accompanying drawings that form part of the same.

15 The invention consists essentially of the novel construction and arrangement, whereby certain members hitherto forming supports and reinforcements to the car structure as distinct parts have in this invention 20 been closely identified with an underframe in order to effect a better distribution of the load.

The objects of the invention are to devise 25 a means of strengthening the structures in certain types of freight and passenger railway cars, so that breakdowns may be avoided and the loads carried with some degree of surety, to repair the older wooden cars, to insure economy in the maintenance of 30 railway rolling stock, to furnish cars that will not be materially affected by the shifting of grain and such like cargoes during shunting operations, and generally to provide a cheap serviceable and durable supporting and reinforcing frame for the car body.

In the drawings, Figure 1 is an end elevation partially in section of the car wall and the underframe, showing the striking 40 plate and the positions of the truss rods in relation to said striking plate and center sill, also the angle bars reinforcing the end wall.

Fig. 2 is a longitudinal sectional view 45 through the center sill showing the intimate relations of the center truss rods to said center sill.

Fig. 3 is a sectional detail showing the 50 truss rod arrangement in the buffer plate of a passenger car.

Fig. 4 is a plan view looking up, showing the truss rod and striking plate construction in relation to the center sill.

Fig. 5 is a plan and sectional view, show-

ing the connections of the reinforcing end 55 wall angles to the side plate in the car body construction.

Fig. 6 is a longitudinal and vertical sectional view of the striking plate and the ends of the truss rods.

Fig. 7 is a longitudinal and horizontal sectional view of the striking plate, showing fragmentary ends of the truss rods.

Fig. 8 is a cross sectional view, showing the outline of a bolster and the positions 65 of the truss rods at and beyond said bolster.

Like numerals of reference indicate corresponding parts in each figure.

Referring to the drawings, the striking plates 1, one at each end of the car, are the 70 communicating members in distributing the load throughout certain supporting and reinforcing parts.

In the striking plates 1, each plate has the upwardly extending inner flange 2 and 75 the outer buffer flange 3 joined by the reinforcing ribs 4 and below said flanges, the customary draft bar opening and buffer surfaces, but it is only with the inner flange 2 and the effect of a knock on the outer 80 flange that this invention has to do.

The flanges 5 and 6 of the striking plates 1 are rigidly secured directly or by connecting angle bars to the longitudinal center sill 7, the latter being formed preferably of a plurality of girders in box like structure and closed in at each end by said striking plates and draft bars, therefore the center sill of the underframe is indissociable from said striking plates so that all shocks coming on the latter are absorbed in said center sill.

The truss rods 8 and 9 are secured at each end by the nuts 10 or other suitable fastening in the flanges 2 of the striking plates 1 95 and extend from each end on and over the saddles 11, mounted on the bolsters 12, and in and under the brackets 13, rigidly secured to the Z-bars 14, the latter being rigidly secured to the center sill 7, said Z-bars 14 100 being preferably mounted and secured beyond said center sill 7 on the cross bearers 14^a, which are centrally set in wooden cars being repaired to permit the application of the center sill of the underframe to the structure.

The brackets 13 are placed as near to the center sill 7 on the Z-bars 14 as the truss rods

8 and 9 will permit, thus reducing the cantilever effect on the said Z-bars 14 to the minimum.

The use of the wooden cross bearers 14^a 5 on each side of the center sill 7 affords in every instance an excellent base for a Z-bar extension beyond said center sill. The said truss rods continue into the turn buckles 15 at the center of the underframe, by means 10 of which the proper tension is applied to said rods.

It will be thus seen that as the bolsters 12 are rigidly secured to the center sill 7 and also the Z-bars 14, the said truss rods 15 throughout their whole length are never apart from intimate association with said center sill, for they are fastened to the permanent ends of said center sill, namely, the striking plates 1, they are supported intermediate of their length on the bolsters 12 and also are strung under the said Z-bars 14 thereby exerting both downward and upward pressure on said center sill as well as a longitudinal strain from their end connections, consequently it may truly be said that the truss rods are quite as good as integral with the under frame, and thus forming the bottom cord of a girder.

The outside truss rods 16 and 17 are not 30 like the center truss rods 8 and 9 as at the ends they are not so intimately associated with the center sill 7, though a more definite connection can be made if desirable, however for the purposes of this invention it 35 is sufficient to emphasize only the central truss rods because of their proximity to said center sill. The truss rods 16 and 17 follow the same course as the truss rods 8 and 9 over the saddles 18 on the bolsters 12 and 40 in the brackets 19 secured to the Z-bars 14 and at their ends are secured in the end sills of the car as according to the present practice for all truss rods.

The Z-bars 20 extend vertically from the 45 flanges 2 of the striking plates 1, to which they are rigidly secured, and are secured by the bolts 21 to the posts 22 of the end walls 23.

The angle bars 24 are secured to the inner 50 sides of the upper transverse beams 25 of the body frame and the bolts 26 secure the Z-bars 20 to said angle bars 24 through said transverse beams 25.

The outwardly projecting section of the 55 angle bars 24 are rigidly secured to one section of the angle bars 27 and the other sections of the latter are rigidly secured to the side plates 28.

It will be understood by the foregoing 60 description, referring to the end wall reinforcing bars, that the underframe and particularly the center sill 7 is connected through said striking plates and Z-bars 20 to the vertical, transverse and longitudinal 65 beams of the body frame practically embrac-

ing the whole car frame both body and under frames in what may be termed, for purposes of explanation, an integral body and supporting frame.

To more pertinently point out the features 70 in this construction, it may be said that in the first place there is the underframe formed of the center sill 7 having the permanent ends in the striking plates 1, the intermediate upper transverse members and 75 the bolsters 12 also rigid with the center sill 7, the intermediate transverse angle bars 14 rigid with said center sill 7 and the central truss rods 8 and 9 secured at the ends to the center sill and intermediately bearing thereon top and bottom, and in the next place the body frame formed of longitudinal vertical and transverse beams, angle bars connecting transverse to longitudinal beams and angle bars connecting vertical to transverse 80 and vertical to the center sill of the underframe, thereby completing a rigidly connected frame structure, in which the strain of load or shock will be distributed, so that the heaviest and strongest parts bear the 90 chief burden of weight or shock.

In applying the truss rod construction herein described to passenger cars the truss rods 29 and 30 are fastened at each end to the plates 31 and 32 of the spring casings 95 at the inner ends of the spring buffer mechanisms 33 and extend over intermediately placed saddles preferably on the bolsters and under brackets supported by a transverse bar toward the center of the car and 100 are adjusted centrally by turn buckles as in the truss rods 8 and 9.

The buffer mechanisms 33 while in themselves comprising resilient members are rigidly attached to the underframe of the 105 car, consequently the truss rods 29 and 30 thereby become closely identified with said underframe.

In the operation of these cars, the underframe is mounted on trucks as customary 110 and takes the load, the weight being distributed between the center sills, the bolsters and the truss rods, proportionately in the order named, as it will easily be understood from the foregoing description of the details that the center sill is the chief support, absorbing as it does much of the weight and strain naturally coming to the bolsters and truss rod, though together they 115 form a structure of much greater capacity 120 for weight bearing than separately, as it will be seen that the center sill strengthens the truss rods and incidentally the said truss rods strengthen the center sill, whereas apart the truss rods would be bearing too 125 much strain and the weight on the center sill would not be lessened.

The effect of the shocks incident to the use of the cars, both in shunting and regular travel, otherwise the bumping of one car 130

against the other, is on the underframe as usual and particularly the center sill as the truss rods do not share to any appreciable extent in this burden, though their intimate association with the underframe renders them less liable to dislocation, simply because they are held so firmly, of course this refers to the central truss rods described in detail hereinbefore.

10 The vertical reinforcing angle bars are particularly efficacious in the shifting of the cargo and in this construction it will be seen that even in such happenings the center sill again absorbs part of the load incident 15 to the extra pressure on the end wall, and thereby the end wall becomes an intermediate part between the upper longitudinal framing and said center sill, consequently the weight is distributed in three places, which 20 will have the effect of materially lightening the pressure on one and save the car from breaking or bulging.

Various changes may be made in the details of the construction herein described 25 without departing from the spirit of the invention so long as they remain within the scope of the claims for novelty following.

What I claim is:—

1. In car construction, a wooden body,

bars secured to the beams of the frame of 30 said wooden body and extending up the end walls, a metal beam forming part of the underframe of the car, plates connecting said metal beam to said bars and truss rods extending from end to end of the underframe and rigid with said plates and metal beam.

2. In car construction, an underframe having a center sill in the form of a box girder, striking plates rigidly secured to the 40 ends of said center sill, truss rods secured in said striking plates, angle bars secured to said striking plates and extending vertically, a body having side and end walls and vertical transverse and longitudinal beams 45 in the framing, said angle bars being secured to vertical beams in said framing, angle bars secured to transverse beams in said body framing and to said vertical angle bars and angle bars securing the transverse beam angles to the longitudinal beams in said framing.

Signed at Montreal, Quebec, Canada, this 27th day of January, 1917.

KARL FRITJOF NYSTROM.
